No 138 James Ultron J. Patent Oct 24 1847

Des. B8

James Albro Jr. Elizabeth town New Jersey.
Letters Patent Design No. 138, dated 24th July 1847

The schedule referred to in these Letters Patent and manning part of the same.

To all whom it may concern: Be it known that James Albro Jr. of Elizabeth town in the County of Essex and State of New Jersey have invented, or produced a new design, or figure to be printed or stamped on floor Oil Cloth, and I do hereby declare that the accompanying drawings are full and exact representations of the same which I claim as my invention and desire to secure by letters patent, not confining myself to the size or colours of the accompanying drawings.
